(57) **CLAIM**

The ornamental design for a candy figurine for a container, as shown and described.

DESCRIPTION

FIG. 1 is a perspective view of a candy figurine for a container according to a first embodiment of the new design. FIG. 2 is a front elevation view of the candy figurine of FIG. 1.

FIG. 3 is a top plan view of the candy figurine of FIG. 2. FIG. 4 is a rear elevation view of the candy figurine of FIG. 2.

FIG. 5 is a bottom plan view of the candy figurine of FIG. 2.

FIG. 6 is a right side elevation view of the candy figurine of FIG. 2.

FIG. 7 is a left side elevation view of the candy figurine of FIG. 2.

FIG. 8 is a perspective view of a candy figurine for a container according to a second embodiment of the new design.

FIG. 9 is a front elevation view of the candy figurine of FIG. 8.

FIG. 10 is a top plan view of the candy figurine of FIG. 9. FIG. 11 is a rear elevation view of the candy figurine of FIG. 9.

FIG. 12 is a bottom plan view of the candy figurine of FIG. 9.

FIG. 13 is a right side elevation view of the candy figurine of FIG. 9; and,

FIG. 14 is a left side elevation view of the candy figurine of FIG. 9.

The broken lines in the figures represent portions of the candy figurine for a container that form no part of the claimed design.
